GLOW LAMP COMBINATION

William D. Stahl, Kenilworth, and Fred V. Collins,
Des Plaines, Ill., assignors to William F. Stahl,
Kenilworth, Ill.

Application March 13, 1946, Serial No. 654,174

1 Claim. (Cl. 176—122)

1

This invention relates to a glow lamp combination and more particularly to a glow lamp having an element therein cut to a given resonant frequency and provided with electron-emitting material in combination with a microwave generator tuned to the resonant frequency of the glow lamp element. The combination is useful in connection with the decoration and illumination of Christmas trees, and other selected structures.

An object of the invention is to provide a combination in which a glow lamp supported upon a Christmas tree or upon some other selected support may be caused to glow through the use of a generator supported at a distance therefrom. A further object is to provide means for illuminating or decorating a structure without the use of wires or current-carrying members and through the use of resonant frequencies. Other specific objects and advantages will appear as the specification proceeds.

The invention is illustrated, in a preferred embodiment, by the accompanying drawing, in which—

Figure 1 is a broken side view in elevation of a Christmas tree equipped with structures embodying our invention; Fig. 2, a vertical sectional view of the glow lamp of the character shown attached to the Christmas tree in Fig. 1; Fig. 3, a vertical sectional view of a modified form of glow lamp; Fig. 4, a vertical sectional view of a modified form of glow lamp equipped with an electric resistance element; and, Fig. 5, another modified form of glow lamp embodying our invention.

In the illustration given, 10 designates a Christmas tree and 11 designates the glow lamp attached thereto. 12 designates a micro-wave generator supported below the Christmas tree on the floor.

The glow lamp 11 may be of any suitable construction. In the illustration given, glow lamp 11 comprises a glass envelop of the L-shape illustrated (or any convenient shape) and is equipped with a glass portion 13 supporting a wire element 14 of the shape illustrated. Any suitable gas, such as argon, may be employed in the envelop. The element 14 is cut to a given resonant frequency and is coated with electron-emitting substance 15, such as tellurium oxide, etc. The coated element will thus emit electrons under the influence of or in an electrostatic or electromagnetic field of micro-wave resonant frequency, and an ionic bombardment takes place causing the gas to fluoresce, thus giving off visible light. The inside of the envelop may be

2

coated with a phosphorescent material 16a, such as standard phosphors, and this gives a phosphorescent light under the influence of the ionized gas.

5 In order to support the lamp upon a Christmas tree or other support, we equip the horizontal leg 16 of the glass envelop with a band 17 of metal or other suitable material, for securing the clamp member 18 thereon. With this structure, the leg member 16 in effect forms the upper handle of the clamp 18 and permits ready attachment of the lamp to any selected portions on the Christmas tree or other support.

In the illustration given in Fig. 3, a modified 15 form of the glow lamp is shown. Here the glass envelop 19 is T-shaped and a pair of wire elements 20 are supported therein by means of the integral glass members 21. The elements are constructed the same as element 14 and are 20 coated in the same manner. To enhance the lighting effect, the vertical elements 20 may be equipped with glass sleeves 22.

Each of the lamps may be partially evacuated 25 for providing low pressure for easy ionization and the lamps may be filled with neon, argon, krypton and other suitable rare gases. Either of the horizontal legs of the glow lamp 19 may be equipped with an attachment clamp of the type illustrated in Fig. 2.

In combination with the glow tubes and at 30 a spaced distance therefrom, we provide a micro-wave generator of well-known construction. The micro-wave generator may be of the usual type which may be tuned to produce different micro-wave frequencies or, if desired, the generator may 35 be of the non-variable type which produces only a given micro-wave frequency which is of the same resonant frequency as the elements 14 or 20 in the glow lamps.

In the construction as illustrated, we have 40 found that a generator producing micro-waves of 200 megacycles is fairly satisfactory for the illumination of the lamps 11 on the Christmas tree. 100 megacycles did not have the field strength at distances from the glow lamp 11 as 45 did the higher frequencies. In other words, we find that the higher the frequency the greater the actual transference of power conveyed by the electromagnetic and electrostatic waves of micro-wave length.

In the operation of the combined structures, 50 the glow lamps 11 and 19 are placed in any desired arrangement upon a Christmas tree or other selected device and in this operation the clamp 18 or any other suitable member is effective in the ready securing of the members in

their desired positions upon the support. The micro-wave generator is located at any suitable point, say, upon the floor under the tree or device, or upon an adjacent table, etc. If the generator is already tuned or constructed so as to produce only the resonant frequency of the elements of the glow lamps, then immediately upon the turning on of the generator, the glow lamps begin to emit or fluoresce with light and an effective lighting effect is produced. The combination obviates all wiring requirements and leaves the Christmas tree or other supporting device entirely unencumbered with wires, etc.

By employing a micro-wave generator which is tunable, we may employ several series of glow lamps in which each series has an element tuned to a different frequency. Thus, by controlling the generator, the different series of glow lamps may be brought successively into play and if the glass envelopes of the different series have different colors, different lighting effects will be thus produced through the control of the generator.

In the modified construction shown in Fig. 4, the resonant elements 23 are connected at their top by a coil of resistance wire 24. A current is set up within the elements 23 under the influence of the micro-wave frequency and the current in passing through the electric resistance element 24 causes the element 24 to become incandescent and thus to give visible light. The structure shown in Fig. 4 will function when evacuated or when filled with inert gas.

In the structure shown in Fig. 5, the envelop 25 is in itself formed to a definite resonant frequency and will, as a whole, act as a resonator under the influence of micro-wave oscillation. The envelop is filled with fluorescent type gas such as argon, neon, krypton, etc. Under the influence of the micro-wave oscillation or frequency, the gas ionizes, causing fluorescence to take place and visible light to be produced.

While we have shown glow lamps in which open circuit resonators are provided, it will be understood that the circuits of said resonators may be of the closed or hairpin type.

While in the foregoing specification, we have set forth certain details as illustrative of certain embodiments of the invention, it will be understood that such details may be varied widely by those skilled in the art without departing from the spirit of our invention.

We claim:

A glow lamp adapted for support upon the branch of a Christmas tree, comprising a translucent, evacuated envelope formed of electric insulating material and having therewithin at low pressure a gas operative to ionize and glow in the presence of a high-frequency electric field, electrically conducting means wholly within the envelope, said electrically conducting means being coated with electron-emitting material, phosphorescent material deposited as a thin coating on the inner surface of the envelope, and a clamp member mechanically secured to the outside of the envelope.
